UNITED STATES PATENT OFFICE.

JOSEPH H. LOWDEN, OF ELYRIA, OHIO.

LIQUID RECEIVING AND CONVEYING DEVICE.

Application filed April 30, 1925. Serial No. 27,115.

To all whom it may concern:

Be it known that I, JOSEPH H. LOWDEN, a citizen of the United States, residing at Elyria, in the county of Lorain and State 5 of Ohio, have invented certain new and useful Improvements in Liquid Receiving and Conveying Devices, of which the following is a specification.

My invention is an improvement in liquid 10 receiving and conveying devices, and particularly to such a device for use in garages or at filling stations and in similar places for catching oil as it is drained from the engine of an automobile.

15 I find in garages and public filling stations, and in similar places that are provided with pits or the like over which an automobile is driven when it is desired to drain the oil from its engine, and where it is desired 20 to install a device for catching the drained oil, that considerable difficulty is experienced in adjusting the oil receiver under the outlet in the engine. I also find that the widths of various pits are not uniform 25 and for this reason difficulty is experienced in providing a support for the oil receiver which may be used in pits of different widths.

It is an important object of my invention, 30 therefore, to overcome these disadvantages by providing a device of the above named character capable of being quickly adjusted to fit pits and other supports of varying sizes.

35 Another object of my invention is to provide a device of the above named character which is extremely simple of construction and inexpensive to manufacture.

Other objects and advantages of my invention 40 will become apparent as the description of an embodiment of my invention progresses, reference being made to the accompanying drawings in which like numerals are employed to designate like characters 45 throughout the same.

In the drawings:

Fig. 1 is a top plan view of my receiver and conveyor device showing the same supported on the sides of a pit;

50 Fig. 2 is a side elevation of my invention showing the adjusting means;

Fig. 3 is a bottom plan view of the device showing how the auxiliary rollers may be adjusted;

Fig. 4 is a transverse section taken on line 55 4—4 of Fig. 2; and

Fig. 5 is a broken perspective view of the carriage support, the view showing only one side of the support.

In the drawings, I provide a frame 60 consisting of side and end members, the side members forming a track for a carriage 6 on which the liquid receiving device 5 is carried. The frame is movably supported on the sides 7 of a pit or the like. In the 65 present showing, the frame is adapted to move longitudinally of the pit upon wooden runways 7 secured to the sides of the pit, although it is to be understood that I may use metal runways or tracks if desired. 70

The frame consists more specifically of two telescoping sections, each comprising a side rail 9 slotted at 10 and 11, and a side rail 12 which carries bolts 13. The side wall of rail 9 is preferably shorter than the rail 75 12 to permit of the greatest amount of inward adjustment of the frame sections. Each of the side rails is provided with a bottom flange 14 and an upright wall 9 or 12, and when the sections are in assembled position one rail 9 of one section will telescope the adjacent rail 12 of the other section. The ends of the side rails are each bent upwardly as at 15 and shaped to form roller supports 16 and 17, and carry rollers 80 18 which are adapted to roll over the tracks 7 on the side of the pit. In this manner the entire frame may be shifted from one end of the pit to the other.

The roller supports 17 are spaced from 90 each other by a spacer bar 19. Likewise, the supports 16 are spaced by a spacer bar 20. This not only affords a more rigid construction for the frame, but also provides for handles on each end of the frame when it 95 is desired to remove the frame from the pit. The spacer bars are secured to the frame by bolts 21 forming a knock-down structure which will be found to be of great advantage in shipping the device, since the various 100 sections may be knocked down and packed closer together.

As previously stated, the frame sections telescope each other for adjustment purposes. Each side rail 12 is provided with adjustment bolts 13 which extend through the side wall of the rail and pass through the adjacent slots 10 and 11 in the side rail 9. 105

A nut 23 and lock washer 24 are provided for each bolt and when the frame sections have been adjusted to the proper width of pit the nuts are tightened to maintain the 5 adjustment.

Referring now more particularly to Fig. 3 in which I have shown a bottom plan view of my invention, I provide at each end of the frame an auxiliary frame 24. Each auxiliary frame is longitudinally adjustable with respect to the main frame and is adapted to be movably secured thereto by means of bolts 25 and nuts 26 passing through slots 27 in the auxiliary frame. Auxiliary rollers 28 and 29 are mounted on the frame 24 and their outer peripheries extend beyond the auxiliary frame to contact with the side walls of the pit when the device is in position. These 10 auxiliary rollers are provided so that the entire frame may be supported in the pit and then more accurately adjusted until the auxiliary rollers contact with the side walls of the pit, insuring a close adjustment with 15 in the pit and at the same time reducing the friction of the ends of the main frame with the pit walls. It will be noted that the adjacent ends 30 and 31 of each auxiliary frame are adjustably secured to the bottom 20 walls 14 and 14', respectively, of the main frame.

Referring now to Figs. 1 and 4 of the drawings, I provide a carriage mounted to move lengthwise of the main frame, comprising angle iron side members 32, each having the flange turned downwardly and each carrying in the flange one or more wheels 33 adapted to support the carriage movably on the side rails 9 and 12 of the 35 main frame. These members 32 are secured together at the ends by a plate 34, which is provided with an opening 35 for the reception of a bucket or other container 5 for receiving the oil from the automobile engine.

40 Suspended below the opening in the plate, is a yoke 36 secured to the flanges of the side members 32. This yoke is slotted at 37 and carries a lever 38 pivoted at 39. The lever is connected at one end to a pivoted 45 plate 40 through a link 41 which reciprocates within the slot 37. Suitable pawl and ratchet mechanism 42 operated by a handle 43 on the lever 38, provides for the vertical adjustment of the plate 40 when the lever is 50 rocked. A container 5 is placed through the opening 35 and rests on the plate 40 and is raised and lowered by operation of the lever 38.

When it is desired to remove the oil from 60 the engine of an automobile, the automobile is driven to a point over the pit and the frame and carriage are adjusted in the pit below the oil outlet in the engine. The lever 38 is rocked to elevate the container for receiving the oil.

A tool rest 45 is provided with supporting arms 46 which are bent at their outer ends to fit into openings 47 in the plate 34 to support the rest on the plate. When in position the tool rest is supported over one edge of the carriage, preferably on the side of the carriage on which the lever 38 is operated, so that the operator will at all times have quick and easy access to the various sized wrenches and tools carried by the openings 48 in the tool rest. A strap 49 is provided below the openings and extends lengthwise of the tool rest to prevent the tools from slipping entirely through the 70 openings.

75 A fork-shaped support 50 is provided on one end of the tool rest and extends over the outer edge thereof and is adapted to support an electric light or cord attached thereto, so that ample illumination may be had for using the device at night. It will be noted that the support 50 moves with the carriage and will at all times give the correct light adjustment regardless of the position of the carriage.

80 It will be seen, therefore, that I have provided an adjustable liquid receiving and conveying device for use in places for receiving materials, and particularly for use at filling stations and the like where pits are provided for drawing oils from automobile engines.

85 My invention provides a very simple apparatus which may be manufactured at 90 moderate cost and which may be readily adapted to use in various sized pits and the like by simply adjusting it to the desired size. My invention also may be readily knocked-down for packing and affords a 95 very compact and simple construction.

100 Various changes may be made in the construction and operation of my invention without departing from the spirit of my invention or the scope of the subjoined claims.

110 I claim:

1. In a device of the class described, in combination, a longitudinally adjustable frame, said frame being movable and comprising side members having upwardly extending flanges to provide wheel runways, a carriage supported on wheels engaging the said runways, and a receptacle carried by the carriage.

115 2. In a device of the class described, in combination, a longitudinally adjustable frame, said frame being movable and comprising side members having upwardly extending flanges to provide wheel runways, a carriage supported on wheels engaging the said runways, and a receptacle carried by the carriage, said receptacle being adjustable vertically, and means for adjusting the receptacle vertically.

120 3. In combination with the side sills of a pit for working under automobiles, parallel 125

- tracks secured to the side sills and extending longitudinally therewith, an adjustable frame extending intermediate said tracks within the pit, rollers supporting said frame, said frame having spaced tracks extending transversely relative to the parallel tracks secured to the side sills of the pit, a carriage having rollers mounted upon the tracks of said frame, and a liquid receiving receptacle carried by said carriage and adapted to be adjusted to a plurality of vertical positions on the carriage.
4. In a device of the class described, in combination, a movable frame, said frame consisting of telescoping sections for adjustment purposes, and having tracks formed thereon, a movable carriage having rollers to engage the tracks of said frame, a liquid receiving receptacle extending through an opening in said carriage, a receptacle supporting member mounted on said carriage beneath the receptacle, and a lever pivotally carried by said carriage for moving said supporting member vertically to engage and maintain the receptacle in any one of a plurality of vertical relations relative to said carriage.
5. In a device of the class described, in combination, a movable frame, said frame consisting of telescoping sections for adjustment purposes and having tracks formed thereon, a receptacle carriage having rollers and movable along said tracks, and means for locking said telescopic sections in any one of a plurality of desired positions.
6. In combination with the side sills of a pit for working under automobiles, parallel tracks secured to the side sills and extending longitudinally therewith, an adjustable frame extending intermediate said tracks within the pit, rollers supporting said frame, said frame having spaced tracks extending transversely relative to the parallel tracks secured to the side sills of the pit, a carriage having rollers mounted upon the tracks of said frame, and auxiliary rollers carried by the frame and having their axes in a substantially vertical plane with respect to the frame, said rollers being adapted to contact with the pit walls to provide for proper adjustment of the frame within the pit.
7. In combination with the side sills of a pit for working under automobiles, parallel tracks secured to the side sills and extending longitudinally therewith, an adjustable frame extending intermediate said tracks within the pit, rollers supporting said frame, said frame having spaced tracks extending transversely relative to the parallel tracks secured to the side sills of the pit, a carriage having rollers mounted upon the tracks of said frame, and auxiliary rollers carried by the frame and having their axes in a substantially vertical plane with respect to the frame, and means for adjusting said rollers in a substantially horizontal plane to provide for proper adjustment of the frame within the pit.
- In testimony whereof I hereunto affix my signature this 27th day of April, 1925.

JOSEPH H. LOWDEN.
